CLAIM

The ornamental design for a projection device, as shown and described.

DESCRIPTION

FIG. 1 is a perspective view of a projection device showing our new design.

FIG. 2 is a top view of the projection device.

FIG. 3 is a bottom view of the projection device.

FIG. 4 is a front view of the projection device.

FIG. 5 is a back view of the projection device.

FIG. 6 is a left-side view of the projection device; and,

FIG. 7 is a right-side view of the projection device.

The broken lines shown in the drawings are for illustrative purposes only and form no part of the claimed design.
